UNITED STATES PATENT OFFICE.

RICHARD W. BURNETT, OF CHICAGO, ILLINOIS.

REVERSIBLE-STRUT BRAKE BEAM.

1,405,665.

Specification of Letters Patent. Patented Feb. 7, 1922.

Application filed December 17, 1919. Serial No. 345,576.

To all whom it may concern:

Be it known that I, RICHARD W. BURNETT, a citizen of United States, residing at Chicago, in the county of Cook and State 5 of Illinois, have invented a certain new and useful Improvement in Reversible-Strut Brake Beams, of which the following is a full clear, concise, and exact description, reference being had to the accompanying 10 drawings, forming a part of this specification.

This invention relates to improvements in reversible strut brake beams.

In the operation of railway cars, it is 15 well known that the struts of the brake beams are sometimes set to the right and sometimes to the left, that is, the struts are positioned at an angle to the vertical sometimes on one side and sometimes on 20 the other in order to provide for the attachment of the brake levers employed in applying the brakes to the wheels of the truck. Heretofore, it has been the common practice for such struts to be made rigid 25 with respect to the brake beams, thereby necessitating the carrying in stock of right-handed and left-handed struts.

One object of my invention is to provide a strut for brake beams, which strut 30 may be reversed or adjusted so as to be usable in either the left-hand or right-hand condition, the adjustment being effected at any time after the brake beam has been completely assembled.

Another object of my invention is to provide a strut for brake beams so attached 35 to the compression and tension members of the brake beam that the column proper of the strut may be replaced or renewed, as well as adjusted, without the necessity of disassembling the brake beam or taking off the strut anchor block which is employed to rigidly secure one end of the strut to the compression member of the brake beam.

The invention furthermore consists in the 45 improvements in the parts and devices and in the novel combinations of the parts and devices herein shown, described and made the subject matter of claims.

In the drawing forming a part of this 50 specification, Figure 1 is a top plan view of a truck beam of a railway car showing my improvements in connection therewith. Figure 2 is an enlarged sectional view taken 55 lengthwise of the strut and corresponding substantially to the line 2—2 of Figure 1.

In Figure 2, parts are broken away in order to accommodate the figure on the sheet and also to more clearly illustrate the construction. Figure 3 is a sectional view taken 60 substantially on the line 3—3 of Figure 2. Figures 4, 5 and 6 are views corresponding respectively to Figure 3 but illustrating different embodiments of my invention.

Referring first to the construction illustrated in Figures 1, 2 and 3, 10 denotes the tension member, 11 the compression member and A the strut of a brake beam of a railway car. The tension member 10 is of bar form and the compression member is 70 channel-shaped as clearly indicated in Figure 2, the construction of these parts being well known and in common use. At the ends of the brake beam are shown the usual heads 12—12.

The improved strut A, as shown, includes what I term an anchor block B, a column C, and a bearing block D. The anchor block in the specific embodiment shown, is that member by which the attachment of the 80 strut to the compression member 11 is accomplished and the bearing block D is that part of the strut which transmits the pressure to the tension member 10. The anchor block B, as shown, is a one-piece 85 member of substantially hollow rectangular form at its outer end as indicated at 13 in Figure 2 and the opening 14 therein is so designed as to properly fit over the channel-shaped compression member of the 90 strut. The anchor block B is held or secured in its position after the parts have been assembled by a wedge key 15 which is driven between the web of the channel and the wall of the anchor block 95 B, the latter having suitable lugs 16—16 to maintain the key against slipping and in effect forming a guide for the key. The key 15 has a bendable tongue 17 at its narrow end which is bent out against the anchor 100 block when the key has been driven home. As will be understood by those skilled in the art, the anchor block B is applied to the compression member 11 before the brake beam has the usual heads applied thereon. 105

The bearing block D of the strut consists of a casting of suitable form having a recess 18 at its outer end which fits over the tension member 10. The bearing block D also has a cylindrical socket 19 on its inner 110 side with a transverse wall or partition 20 at the bottom thereof thereby forming a

5 pocket or bearing for the correspondingly shaped end 21 of the column C. A swivel joint is effected between the bearing block D and the column C by means of the rivet 22, there being suitable clearance provided for that end of the rivet adjacent the tension member 10. The bearing block D is 10 preferably provided with upstanding ears 23 suitably perforated as indicated at 24 15 to adapt the brake beam for a third point suspension.

The column C is provided with a longitudinally extending slot 25 into which the 20 truck or brake lever may be inserted and 15 secured to the column by a pin or bolt passing through the lever and holes 125 in the arms of the column C.

In order to provide for the adjustment or reversing of the strut to adapt it for right 25 and left-hand operation, I employ the following structure. The anchor block B is extended inwardly from the compression member 11 of the brake beam by means of flanges 26—26 which are merged on one side 30 as indicated at 27 in Figure 3. The flanges 26—26—27 are so formed as to provide a half bearing 28 for a journal section 29 integrally formed on the column C. It will be noted that the said flanges 26—26 extend 35 parallel so that the journal section 29 of the column C may be inserted within this bearing provided on the anchor block B, from a lateral direction and this is true even when the block B is secured in place on the compression member 11 of the brake beam. The remainder of the bearing for the journal section 29 of the column C is provided by a combined spacer and bearing cap designated by the reference E. Said spacer cap E fits 40 between the two flanges 26 and is securely riveted thereto as by means of the rivet 30 which passes through suitably aligned perforations in the flanges 26 and cap E. The inner side of the cap E is curved as indicated 45 at 31 to conform to the circumference of the journal section 29 so that the column may oscillate within the two-part bearing described. In order to transmit the pulling forces between the column C and the anchor 50 block B, that is between the strut and the compression member 11 of the brake beam, the column C is formed with an annular flange 32 at its extreme end adjacent the anchor block B. The block B is provided with 55 a corresponding semi-annular groove or recess 33 to accommodate said flange 32, shoulders 34 being thereby provided on the block B to transmit the longitudinal pulling forces. The side walls of the recess 33 are made tangent 60 as indicated at 35 in order to permit of the introduction of the flange 32 as will be understood. In order to provide greater bearing for the flange 32, the combined spacer and bearing cap E is extended to the 65 left, as viewed in Figure 2, and provided

with an arcuate flange 36 which bears against the flange 32.

The standard practice in the use of brake beams is to extend the truck lever at an angle of 40° to the vertical, either right or left 70 and in order to properly gauge this angle and bring the column C of my improved strut to rest in either of the proper right or left positions, the flange 32 of the column is formed with a lug or extension 37 of substantially triangular shape, the side edges 38—38 thereof being so positioned that, when the edge 38 lies against a side 35 of the opening 33, as indicated by one of the dotted positions in Figure 3, the column C will be at its 80 proper 40° angle.

With the construction hereinbefore described, it is evident that the strut can be adjusted or reversed after it has been assembled with the brake beam by merely employing a bar or lever to properly turn it. It will also be noted that, in the event of breakage of the column proper of the strut, the column may be replaced without the necessity of disassembling the entire brake 90 beam since the connection between the anchor block B and the column A can be broken by shearing the rivet 30 and the column replaced and a new rivet 30 substituted, the foregoing being due to the fact 95 that the column can be swung laterally with respect to the anchor block B, and such movement is not interfered with by the bearing block D on the tension rod 10.

In Figure 4, the arrangement is quite similar to that shown in Figures 1, 2 and 3 except that the limiting lug 137 is formed on the opposite side of the journal section 129 of the column and works within an arcuate recess 133 formed in the anchor block B'. 100 The arcuate recess 133 is in reality an enlargement of the semi-annular recess 133A provided in the block B' for the annular flange 132 formed on the column of the strut. A combined spacer and bearing cap E' is 110 employed riveted to the anchor block B' in the same way as in the construction shown in Figures 1, 2 and 3.

In Figure 5, the arrangement is substantially the same as that shown in Figure 3 115 except that the flange 232 formed on the column of the strut is notched or cut away as indicated at 50 and the cooperating limiting stop or lug 237 is formed on the combined spacer and bearing cap E''. It will be evident that the rotative movements of the column are limited by the lug 237 engaging the flange 232 at either end of the slot 50.

In the construction illustrated in Figure 6, the journal section of the column of the 125 strut is indicated by the reference 329; the anchor block by the reference B³ and the bearing cap by the reference E³. In this construction, the bearing cap is provided with arms 51—51 which straddle the adj- 130

cent portions of the anchor block B³ and are riveted to the latter as by the rivet 330. Any one of the means for limiting the rotative movement of the column shown in Figures 3, 4 and 5 may be employed with the construction illustrated in Figure 6 as will be obvious to those skilled in the art.

Although I have herein shown and described what I now consider the preferred manner of carrying out the invention, the same is merely illustrative and I contemplate all changes and modifications that come within the scope of the claims appended hereto.

16 I claim:

1. In a brake beam for cars having a tension member and a compression member, a strut, said strut comprising, an anchor block adapted to be united to said compression member, a bearing block adapted to be seated against said tension member, and a column extending between said anchor and bearing blocks and swiveled to both of them, the swivel connection between said column and anchor block including a laterally open bearing in one of said elements, a corresponding journal section in the other of said elements, a bearing cap, and overlapping shoulders on said elements whereby, upon removal of said bearing cap, the column may be removed from the anchor block without disturbing the connection of the latter with the compression member of the beam.

2. As an article of manufacture, a reversible strut for brake beams having a tension member and a compression member, said strut comprising; a one-piece anchor block having an opening therethrough adapting it to be slipped over one of said members, a column, and a bearing block, said column and bearing block having a pivotal connection, said anchor block and the column being one of them provided with a journal section and the other with an integral bearing having a lateral opening therefrom whereby the column may be removed from the anchor block while the latter remains in place on the brake beam member, said anchor block and column having a cooperating annular flange and groove whereby longitudinal pulls from the column may be communicated to the anchor block.

3. As an article of manufacture, a reversible strut for brake beams comprising; a one-piece anchor block, a column, and a bearing block, the column and bearing block being adjustably connected, said anchor block having an integral journal bearing and the column having a cooperating journal section, said column having an annular flange and the bearing block having a cooperating annular recess therefor, and means for limiting the relative rotation between the column and the anchor block.

65 4. As an article of manufacture, a strut

for brake beams comprising; an anchor block adapted to be rigidly secured to the compression member of a brake beam, said anchor block having a laterally open bearing formed integrally thereon and provided also with an annular recess, a column having a journal section cooperable with said bearing of the anchor block and provided also with an annular flange working in said annular recess, said flange being formed integrally with the column, the column and block being assembled by movement of the one transverse of the other through said lateral opening of the bearing without disturbing the attachment between the block and the compression member, and means for holding the anchor block and column in assembled relation.

5. In a brake beam for railway cars, the combination with a tension member and a compression member; of a strut comprising, an anchor block fitted over said compression member and fixed in position thereon, a bearing block seated against said tension member, and a column interposed between the anchor block and the bearing block, said column being swiveled with respect to the anchor block and the bearing block, the swivel connection between the column and the anchor block comprising a laterally open bearing on the block, a journal section on the column, a flange on the column bearing against a corresponding shoulder provided on the anchor block, and a bearing cap formed separately from the anchor block and secured thereto.

6. As an article of manufacture, a reversible strut for brake beams, said strut comprising; an anchor block having a semi-cylindrical bearing with an opening of a width equal to the diameter of the bearing, leading laterally therefrom and formed integrally with the block, said block being provided also with an annular recess adjacent said bearing, a slotted column to which the truck lever is adapted to be pivoted, said column having a journal section cooperating with said bearing and adapted to be inserted therewithin through said opening, said column having also an annular flange disposed within said recess, a bearing cap fitting over said journal section within said opening and secured to and cooperating with said anchor block to retain the column in position, means providing for a lost motion of predetermined amount between the column and anchor block, and a bearing block swiveled to the opposite end of said strut.

7. As an article of manufacture, a reversible strut for brake beams having a channel-shaped compression member and a tension member, said strut comprising: a bearing block adapted to be seated on the tension member; an anchor block having a substantially rectangular opening therethrough

adapted to accommodate the channel-shaped compression member therewithin, said anchor block having wedge guiding lugs within said opening so located as to come 5 opposite the web of the channel-compression member whereby a wedge key may be driven between the web of the channel-compression member and the opposed wall of the anchor block to retain the anchor block securely in 10 position; and a column extending between said anchor block and the bearing block and attached at its ends to said blocks.

8. As an article of manufacture, a reversible strut for brake beams comprising; an 15 anchor block adapted to be attached to the compression member of a brake beam, a bearing block, and a column, the column being rotatably mounted with respect to the bearing block, said anchor block having a 20 journal bearing and the column a cooperable

journal adapting the column to rotate with respect to the anchor block, said column being separable from the anchor block while the latter remains attached to the compression member of the brake beam, cooperable 25 annular shoulders on said anchor block and column preventing movement of the column longitudinally with respect to the anchor block, and cooperable shoulders disposed transverse to the annular shoulders, on said column and one of said blocks, arranged to limit the rotation of the column with respect to the anchor block.

In witness that I claim the foregoing I have hereunto subscribed my name this 26th 35 day of November, 1919.

RICHARD W. BURNETT.

Witness:

META SCHMIDT.
